SPOOL OR REEL

Robert V. Olson, Attleboro, Mass., assignor to
Mossberg Pressed Steel Corporation, a corpora-
tion of Massachusetts

Application February 17, 1938, Serial No. 190,894

12 Claims. (Cl. 242—123)

This invention relates to a spool or reel of the type formed of sheet stock; and has for one of its objects the provision of a spool or reel which will have an unusually strong head so that when copper wire is reeled upon the spool and heated for annealing which provides considerable more expansion of copper wire because of its different co-efficient of expansion than the steel of the spool, the strains exerted will be resisted and the heads will maintain their shape in planes at right angles to the axis of the body of the barrel.

Another object of the invention is the provision of a spool having the desired strength in the head and yet one which will have a seamless joint at the corner where there usually exists a seam between the inner surface of the head and the outer surface of the barrel.

Another object of the invention is the provision of a spool having all of its parts welded together that a rigid and strong structure may be provided.

Another object of the invention is the provision of a structure which will so support the stresses as to remain concentric whereby to permit of high speed drawing without wobbling or chattering of the spool on its supports.

With these and other objects in view, the invention consists of certain novel features of construction, as will be more fully described, and particularly pointed out in the appended claims.

In the accompanying drawing:

Fig. 1 is a sectional view through the new spool of this invention;

Fig. 2 is an exploded view of the several parts which go to make up one of the heads of the spool;

Fig. 3 is a fragmental end view of the head of the spool;

Fig. 4 is a sectional view of the parts shown in Fig. 2 in assembled relation and on a much larger scale than shown in Fig. 1;

Fig. 5 is a sectional view of a modified form of spool embodying the thoughts of this invention.

It is found in the use of spools, such as are used for annealing copper wire, that when the loaded spool is heated that the expansion of the copper wire being greater than the expansion of the steel of the spool causes tremendous stresses to be exerted on the head of the spool and often a warping of the head of the spool; and in order that a wire may be drawn at high speeds it is essential that the spool be accurate and concentric with the center hole, and accordingly I have so constructed a spool that the

strains may be resisted sufficiently to prevent the spool from getting eccentric or any part moving beyond the tolerances allowed for high speed production; and the following is a more detailed description of the present embodiment of this invention, illustrating the preferred means by which these advantageous results may be accomplished:

With reference to the drawing, 10 designates the barrel of the spool and 11 the head which is provided from a plate portion 12 having a central hole with a flange 13 extending inwardly about this hole and of a size to abut the end of the barrel 10. The outer portion of this plate is rolled as at 14 to strengthen the edge thereof. A strengthening plate 15 is also provided with a central hole and has a flange 16 extending inwardly about this central hole which is of an external diameter to snugly fit the internal wall 17 of the barrel and is of a length to extend inwardly across the joint 18 formed by the abutting end of the flange 13 and the end of the barrel 10. An outer plate 19 centrally embossed as at 20 abuts the surface of the plate 15 and is provided with a central opening having an internal flange 21. A central tube 22 extends through the opening in the plate 19 and is provided with raised portions 23 which abut the end of the flange 21 while the end of the tube 22 is rolled outwardly as at 24 to extend over the outer portion of the plate adjacent its central opening to tie the outer plate firmly against the inner plate 15 and both plates against the heads of the spool.

The plates 15 and 19 extend outwardly along the head a major portion of its distance from the center opening in the head and are spot welded as at 25, 26 to each other and to the head so as to firmly secure these parts in this assembled relation and prevent any sliding movement of the parts one on the other, such as might tend to occur were the head to be forced outwardly from its right angular position with the barrel. There is also a weld 28, 29 similar to the weld 25, 26 performed at the joint 18 which secures the abutted ends of the barrel 10 and the flange 13 together as at 28 and both to the flange 16 as at 29 that a very strong connection of joint may be had at this location.

By reason of the curved portion of the stock forming the flange 13 a closed joint is formed between the head and the barrel at the right angular meeting of the inner surface of the head and the outer surface of the barrel which is of advantage in that it prevents wire from catch-

ing in the crevice, thus, sometimes formed and also is of advantage in strengthening the structure.

In the showing in Fig. 5 I have carried inwardly the flange 16a as at 30 and turned the same again axially outwardly as at 31 to extend along the tube 22 while instead of providing abutments 23 on the tube 22 I cause this portion 31 to provide the abutments to engage the end 32 of a slightly further inwardly extended flange 21 on the outer plate. This modified form by which the tube 22 is better supported is otherwise the same as shown in the previous Figures 1 to 4 and similarly welded.

I have referred to the fastening means between the parts as welded and by this term I wish to include the equivalent process and means sometimes called "brazing" or any means for uniting the parts that they will not relatively move.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a reel or spool of sheet material, a barrel, a head at the end thereof forming a joint therewith and having a central opening therein of approximately the size of the barrel, an end plate abutting the outer surface of said head and having a flange extending into the opening of said head and barrel to extend across the joint between said head and barrel, a second plate engaging the outer surface of the first said plate and spanning said opening, and welding means for securing the parts in such position, said first plate being of a diameter not less than that of the diameter of said second plate.

2. In a reel or spool of sheet material, a barrel, a head at the end thereof forming a joint therewith and having a central opening therein of approximately the size of the barrel, an end plate abutting the outer surface of said head and having a flange extending into the opening of said head and barrel to extend across the joint between said head and barrel, a central tube, a second plate engaging the outer surface of the first said plate and spanning said opening, welding means for securing the parts in such position said second plate having an inwardly extending flange receiving the end portion of said central tube and abutting a portion thereof to assist in holding said second plate against said first plate, said first plate being of a diameter not less than that of the diameter of said second plate.

3. In a reel or spool of sheet material, a barrel, a head at the end thereof having a central opening and provided with an inturned flange about said opening to abut the end of the barrel and of a relatively small axial extent compared to said barrel, a plate abutting the outer surface of said head and having a flange extending into the opening in said head and across the joint of the head flange with the barrel, a second plate engaging the outer surface of the first said plate and spanning said opening, and welding means for securing the parts in assembled position.

4. In a reel or spool of sheet material, a barrel, a head at the end thereof having a central opening and provided with an inturned flange

about said opening to abut the end of the barrel and of a relatively small axial extent compared to said barrel, a plate abutting the outer surface of said head and having a flange extending into the opening in said head and across the joint of the head flange with the barrel, a second plate engaging the outer surface of the first said plate and spanning said opening, welding means for securing the parts in assembled position, and a central tube engaging said outer plate to assist in holding it against said inner plate and head.

5. In a reel or spool of sheet material, a barrel, a head at the end thereof having a central opening and provided with an inturned flange about said opening to abut the end of the barrel and of a relatively small axial extent compared to said barrel, a plate abutting the outer surface of said head and having a flange extending into the opening in said head and across the joint of the head flange with the barrel, a second plate engaging the outer surface of the first-mentioned plate and spanning said opening, welding means for securing the parts in assembled position, and a central tube engaging said second plate to assist in holding it against said first-mentioned plate, said flange on the first-mentioned plate having a portion thereof inward of said joint extending radially inwardly to engage said tube.

6. In a reel or spool of sheet material, a barrel, a head at the end thereof having a central opening and provided with an inturned flange about said opening to abut the end of the barrel and of a relatively small axial extent compared to said barrel, a plate abutting the outer surface of said head and having a flange extending into the opening in said head and across the joint of the head flange with the barrel, a second plate engaging the outer surface of the first-mentioned plate and spanning said opening, welding means for securing the parts in assembled position, and a central tube engaging said second plate to assist in holding it against the said first-mentioned plate, said flange on the first-mentioned plate having a portion thereof inward of said joint extending radially inwardly to engage said tube and thence extending outwardly along and in engagement with said tube.

7. In a reel or spool of sheet material, a barrel, a head at the end thereof having a central opening and provided with an inturned flange about said opening to abut the end of the barrel and of a relatively small axial extent compared to said barrel, a plate abutting the outer surface of said head and having a flange extending into the opening in said head and across the joint of the head flange with the barrel, a second plate engaging the outer surface of the first-mentioned plate and spanning said opening, welding means for securing the parts in assembled position, and a central tube engaging said second plate to assist in holding it against said first-mentioned plate said flange on the first-mentioned plate having a portion thereof inward of said joint extending radially inwardly to engage said tube and thence extending outwardly along and in engagement with said tube, said second plate having an inwardly directed flange engaging said tube and abutting the end of said outwardly extending portion of the flange of the first-mentioned plate.

8. In a reel or spool of sheet metal, a head having its stock deflected to provide an inwardly extending flange forming a part of the barrel, a tubular member abutting said flange and continuing said barrel, a cylindrical sleeve in said

barrel extending on either side of the junction of said flange and tubular member, and a weld at said junction to secure said flange and member together and said sleeve to said flange and tubular member.

9. In a reel or spool of sheet metal, a head having its stock deflected to provide an inwardly extending flange forming a part of the barrel, a tubular member abutting said flange and continuing said barrel, a cylindrical sleeve in said barrel extending on either side of the junction of said flange and tubular member, and a weld at said junction to secure said flange and member together and said sleeve to said flange and tubular member to bridge the junction between 15 said flange and tubular member.

10. In a reel or spool of sheet metal, a head having its stock deflected to provide an inwardly extending flange forming a part of the barrel, a tubular member abutting said flange and continuing said barrel, a central tube, an end plate abutting the outer surface of said head and having a sleeve extending into the opening of said head and barrel to extend across the joint between said head and barrel and then extending 20 radially inwardly to engage said tube, and a weld at said joint to secure said flange and tubular

member together and said sleeve to said flange and tubular member.

11. In a reel or spool of sheet metal, a head having its stock deflected to provide an inwardly extending flange forming a part of the barrel, a tubular member abutting said flange and continuing said barrel, a cylindrical sleeve in said barrel extending on either side of the junction of said flange and tubular member, and a series 10 of spot welds at said junction and in mutually spaced relation to secure said flange and member together and said sleeve to said flange and tubular member.

12. In a reel or spool of sheet metal, a head having its stock deflected to provide an inwardly extending flange forming a part of the barrel, a tubular member abutting said flange and continuing said barrel, a central tube, an end plate abutting the outer surface of said head and having a sleeve extending into the opening of said head and barrel to extend across the joint between said head and barrel and then extending 20 radially inwardly to engage said tube, and a series of spaced spot welds at said joint to secure said flange and tubular member together and said sleeve to said flange and tubular member.

ROBERT V. OLSON.
